UNITED STATES PATENT OFFICE.

JOHN H. GAVIN, OF CHICAGO, ILLINOIS, ASSIGNOR TO THE L. WOLFF MANUFACTURING COMPANY, OF SAME PLACE.

DESIGN FOR A DRAIN-BOARD FOR SINKS.

SPECIFICATION forming part of Design No. 33,465, dated October 30, 1900.

Application filed September 28, 1900. Serial No. 31,452. Term of patent 14 years.

To all whom it may concern:

Be it known that I, JOHN H. GAVIN, a citizen of the United States, residing at Chicago, in the county of Cook and State of Illinois, have invented and produced a new and original Design for a Drain-Board for Sinks, of which the following is a specification, reference being had to the accompanying drawings, forming a part thereof.

The principal feature of my new drain-board design consists in a rectangular-shaped drain-board, of enameled iron, having rounded corners at one end and at the other end ogee-curved corners, forming a tapering mouth contracting from both of the side edges of the board, the whole being surrounded by a marginal rolled rim, except at the mouth edge, which has a downward curve, and the surface of the board being furnished with a series of parallel longitudinal grooves extending from the mouth edge to near the rear end of the board, the two outside grooves having curved portions uniting the same with the next inner adjacent groove near the mouth end of the board, thus giving the board a perfectly symmetrical shape and appearance and adapting it for application to the sink at either end thereof, or, in other words, adapting it for use as either a right-hand or a left-hand board without in either case changing its general appearance or effect in connection with the sink.

In the accompanying drawings, forming a part of this specification, Figure 1 is a plan view of an enameled-iron drain-board embodying my design, and Figs. 2 and 3 are sections on lines 2 2 and 3 3 of Fig. 1.

In the drawings, A represents an enameled-iron drain-board for a sink, the same having

rounded corners a a at its rear end and ogee-curved corners a' a' at its other end, forming a tapering mouth a^2 , contracting from both the side edges of the board. Surrounding the board is a marginal rolled rim b , except at its mouth edge, which has a downward-curved lip b' . The flat surface d of the board within the marginal roll b is furnished with a series of parallel longitudinal grooves or channels d' , extending from the mouth edge of the board to near its rear end, the open space d^2 between the roll b and the rear ends of the grooves d' substantially equaling in width the space d^3 between each of the outer grooves d' and the marginal roll b at the side edges of the board, thus giving the effect and appearance of a surrounding border of equal width around the board inside the marginal roll, except at the mouth edge. The two outer grooves d' each have curved portions d^4 near the mouth edge of the board connecting the same to the next adjacent groove d' .

As my new design gives a symmetrical shape to the drain-board by reason of the ogee-curved corners a' a' and the tapering mouth contracting from both side edges of the board, my new drain-board may be applied to either the right-hand end or to the left-hand end of the sink without destroying its proper effect and appearance.

I claim—

The design for a drain-board for sinks, as herein shown and described.

JOHN H. GAVIN.
